The ornamental design for a hand grip portion for a mop, as shown and described.

DESCRIPTION

FIG. 1 is a perspective view of a hand grip portion for a mop in accordance with the present invention; and,

FIG. 2 is an enlarged side view of the hand grip portion of the mop of FIG. 1.

The broken line at the bottom of the solid line hand grip portion represents an unclaimed boundary of the design. The broken lines showing the remainder of the mop are for illustrative purposes only and form no part of the claimed design.
